CLAIM

The ornamental design for a combination cooler, tackle box, seat and fishing rod holder, as shown and described.

DESCRIPTION

FIG. 1 is a top, front, left side perspective view of a combination cooler, tackle box, seat and fishing rod holder embodying my design;

FIG. 2 is a top plan view thereof;

FIG. 3 is a bottom plan view thereof;

FIG. 4 is a front elevational view thereof;

FIG. 5 is a right side elevational view thereof, the left side elevational view being a mirror image thereof;

FIG. 6 is a rear elevational view thereof;

FIG. 7 is a cross sectional view as seen along lines 7—7 in FIG. 2; and,

FIG. 8 is an exploded perspective view showing the cooler and seat removed from the tackle box.
